UNITED STATES PATENT OFFICE.

EARL D. SMITH, OF DELPHI, INDIANA.

CAN-CLOSING MACHINE.

Application filed April 29, 1922. Serial No. 557,481.

To all whom it may concern:

Be it known that I, EARL D. SMITH, a citizen of the United States, residing at Delphi, in the county of Carroll and State of Indiana, have invented certain new and useful Improvements in Can-Closing Machines; and I do hereby declare the following to be a full, clear, and exact description of the invention, such as will enable others skilled in the art to which it appertains to make and use the same.

This invention relates to can closing machines, and has for its object to provide a means that will more effectually close the cans than those heretofore proposed.

With this and other objects in view, the invention consists in the novel parts and combinations of parts constituting the can closing means; all as will be more fully hereinafter disclosed and particularly pointed out in the claims.

Referring to the accompanying drawings forming a part of this specification, in which like numerals designate like parts in all the views:

Figure 1 is a front elevational view of a well known type of can closing machine with my invention applied thereto;

Figure 2 is a sectional view of one form of can holding chuck before the rubber or other friction material is applied thereto;

Figure 3 is a view of a chuck of a form slightly different from that shown in Figure 2, with a rubber gasket in place;

Figure 4 is an enlarged sectional view of a portion of the can closing mechanism shown in Figure 1;

Figure 5 is a view similar to Figure 4, but showing the can in position to be closed;

Figures 6, 7, 8 and 9 are sectional views partially broken away, illustrating certain steps of the can closing process;

Figures 10 and 11 are diagrammatic views illustrating how the metal of the can seam is sometimes distorted by the machines in common use;

Figure 12 is a diagrammatic sectional illustration of the parts of a can seam before the closing process;

Figure 13 is a sectional view of the completed seam;

Figure 14 is a plan view of the serrated can support employed during the can closing process; and

Figures 15 and 16 are diagrammatic il-

lustrations showing how the can seams are sometimes indented or distorted during the can closing process prior to this invention.

In order that the precise invention may be the more clearly understood it is said: It is well known that tin cans are commonly automatically closed by highly specialized machines employing a plurality of rollers which revolve around the stationary rim of the can so fast that as many as sixty cans per minute may be closed air tight. But it is also well known that as certain parts of these automatic machines wear the seams around the rims of the cans become more and more defective, and this fact, owing to the enormous number of cans closed, causes in the aggregate very great financial losses every year. Therefore, this invention when more precisely stated has for its object to provide a means for very greatly lessening these losses, and, in fact, to substantially eliminate them.

Referring more especially to Figure 1, there is illustrated a well known type of can closing machine now in general use, where-
in 1 indicates generally well known mechanism for automatically feeding the cans 2 to a support 3, and 4 represents the well known means for carrying away the cans after they have been closed. Each can 2 is automatically elevated by the well known means 5, and its associated parts, until a chuck such as 20, Figure 9, is fitted tightly into the cavity of its head, so that the can is held firmly against rotation between said chuck 20 and said support 3. In order to prevent the rotation of the can around its vertical axis during the closing operation, the surface of the support 3 is serrated as at 7 (Figure 14) and so long as these serrations bite into the bottom rim of the can little or no trouble with leaks through the seams is experienced, for the can is effectually prevented from rotating under the action of the seam forming or crimping rollers. That is, the closure parts of the can are subjected to the action of a plurality of seam forming rollers 8 and 9, at first when in the position they occupy in Figure 12 wherein the lip 10 of the edge of the cover 11 overhangs the outwardly flared edge 13 of the body of the can 2, and a seam closing roller 14 co-acts with the lip 10 to roll the parts into the positions shown in Figure 7, all in a manner well known.

While the roller 14 is thus forming a rolled or rounded seam around the rim of the can, it is followed by a second roller 15, which flattens out the seam as is illustrated in Figures 8 and 9.

In other words, as is well known, there are a plurality of rollers such as 14 and 15 which are supported on the member 16 (Figures 4 and 5), and which revolve so rapidly around the rim of the can while the latter is held stationary between the chuck 20 and the serrated bottom support 3, that the rim seams 17 are often rolled, flattened, and finished in the short space of less than a second, so that the entire operation is very rapid indeed.

But if air tight seams are to be produced, it is well known that the old style of chuck 20, Figure 9, has to fit the cavity 20 in the can head snugly, as illustrated in said figure. But again as said chuck, of necessity, has to enter into and to be withdrawn from can heads with great rapidity, it is evident that in time its rim 31 must wear, so that a loose fit inevitably results, as indicated at 21, in Figure 8. Further, as the cans are automatically fed to the steel serrated surface 7 and may be jammed tightly thereon, at the rate of one a second, it is evident that said surface soon wears also, with the result that with the old type of chuck 20 the crimping or seaming rollers in time will, during their can closing operations, cause some of the cans operated on to turn around their vertical axes, for there is found to be not enough friction between the metal surface of the bottom of the chuck 20 and the can top 11 to prevent this rotation of the can.

When this rotation occurs, instead of the rollers continuing their travel around the can rim, they carry the said rim around with them, and thus operate on a single spot, or point, of the rim, instead of around the entire circumference thereof. This single spot may occur at any point of the circumference, but it usually occurs at or near the vertical side seam 22 of the can (see Figure 15), and a depression or indentation 23 is thus formed in the rolled seam.

When this dent 23 occurs near the seam 22, some of the previously rolled portion 24 of the seam formed by the rounded groove 25 of the roller 14, is left undisturbed, while another part of said rolled portion 24 has been flattened as at 26 (see Figures 15 and 16) by the flattened groove 27 of the roll 15. The result is where the flattened and rounded portions of the seam meet, a lack of uniformity in the seam occurs, which latter gives rise to a leak, all as is further well known.

This defect is often aggravated due to the fact that owing to the presence of the vertical seam 22, and the extra thickness

of metal at such spots as 23, other distortions as indicated at 28 and 29, are found on the inside of the can rim.

But as above stated so long as the parts are new and no wear has occurred, or so long as the can body does not rotate on its vertical axis, the above mentioned objections are not found to take place.

On the other hand, even when such rotation does not occur, a second set of defects develop in the machines at present in use as follows: When the old style chuck 20 fits tightly the can head as it must do and as is illustrated in Figure 9, it is sometimes found that the metal of the can rim opposite the vertical seam 22 is forced over and forms a thin lip or projection 30 as indicated in said figure. When this occurs, the sudden jerking or forcing the chuck rim 31 out of the cavity of the can head lifts and tears out said lip 30 or carries it from the position shown in Figure 9 to that shown in Figures 10 and 11. The result is a leak at the point 32, Figure 11.

Although it is recognized that the foregoing sources of leaks in cans as now sealed by the machines in use apply to a very small percentage of the cans closed in this country, yet, when it is realized that the total number of cans operated on is so large as to make the financial losses due to these leaks very great, the problem of stopping them becomes of tremendous importance. One can not increase the friction between the bottom of the can and the supporting surface because this surface must be smooth to permit the cans to be fed thereto, and fed therefrom with great celerity. One cannot prevent the rims 31 of the chucks 20 from wearing and permitting the cans to rotate owing to the very hard usage to which they are subjected in practice, and besides even if one could prevent this wear, the lips 30 would form anyway, and cause a very considerable financial loss in themselves, and heretofore there has seemed no way to proceed except to find out the above defects after the leaks and losses had occurred, and to then renew the parts which every canner knows is both vexatious and costly.

In carrying out this invention, on the other hand, I have solved the above problem and avoided the above objections by the simple expedient of placing a rubber, or other friction creating and yielding surface, gasket, or member 40, in the can head holding chuck 6. That is, I may conveniently provide the prior chucks 20 with an annular recess such as 41, Figure 2, or I may make entirely new chucks, 6, such as are illustrated in Figures 2 and 3, and provide them with a yielding friction generating means of any suitable material, but preferably in the form of a rubber gasket 130

40. The lower edge 42 of this gasket preferably extends slightly below the lower edge 43 of the chuck, as illustrated in Figures 1, 3 and 6, to facilitate the operation, as will 5 presently appear.

In providing the friction means 40, I do not disturb in any manner the parts nor the operation of the highly specialized and complicated machines now in common use, 10 which is an important feature of this invention, for otherwise, all sorts of troubles would be encountered.

In the operation of this invention, the prior machines are equipped with the improved chuck 6 having the gasket 40. The cans are fed to the serrated supporting surface 7 in the usual manner; said cans are jammed up against the surface 42 of the gasket 40 in the usual manner. The chuck 20 6 is cut away at the points 75 and 76, to accommodate the rubber 40 when compressed, (see Figure 7), and in operation said surface 42 is raised from the position shown in Figure 6 to that shown in Figure 25 7, due to the compression of the said gasket 40. Friction is accordingly generated between said surface 42 and the can top 11 when the crimping action of the rollers begin which is sufficient to prevent the can 30 from rotating on its vertical axis whether or not the rim of the chuck 6 is worn, or whether or not the surface 7 is smooth. In fact, actual tests have shown that it is a positive advantage to have the rims 45 of 35 the chucks 6 slightly smaller than the cavity in the can top, for it is found that with these loosely fitting rims indicated in Figure 8, the burs or lips 30 are not so liable to form, and when they do form, owing 40 to the smaller size of the rims 45, they are more easily disengaged from the can tops without tearing the metal in the manner indicated at 32, than is the case when larger rims 45 are employed.

45. It is a distinct advantage to have the surface 42 of the rubber 40 project slightly below the surface of the chuck 6, because the can cover 11 is steadied and held firmly in place before the crimping rollers 14 50 touch it. And to this end the cut away portions 75 and 76 are important for they permit the rubber to spread out, and thereby permit the chuck rim to enter the cavity in the can top.

55. It therefore results that with the employment of my improved chucks one is enabled to seal cans as tightly and with as much certainty when using worn chucks and serrated supports as when using new ones. Also, 60 one in all cases when using my improvements is less liable to produce leaks through tearing the seams as illustrated at 30. As a matter of fact, I have made tests which showed that out of 24,000 cans closed with 65 the prior chucks 20, about 400 proved defec-

tive from the above causes, while out of 72,000 closed with a worn base plate 3 and a chuck employing my gasket 40, not a single seam proved defective. When it is remembered that there are probably over four billion cans closed annually in this country, it will be realized that a saving of even 200 cans out of 24,000 will be an immense improvement. On the other hand, I have every reason to believe that this invention 75 will substantially eliminate the entire loss now sustained.

It is obvious that those skilled in the art may vary the details of construction as well as the arrangement of parts without departing from the spirit of the invention, and therefore I do not wish to be limited to the above disclosure except as may be required by the claims.

What is claimed is:

1. The process of automatically closing cans which consists in feeding said cans to a support; raising said cans successively into a gripping contact between said support and a compressible friction generating 90 surface with a force sufficient to prevent said cans from rotating on their axes during the crimping operation; and while so held against rotation on their axes revolving a plurality of crimping rollers around and 95 in contact with the rims of said cans to effect air tight closures, substantially as described.

2. The process of automatically closing cans which consists in feeding said cans 100 successively to a support; raising said cans successively into a gripping contact between said support and a yielding friction generating surface with a force sufficient to prevent rotation on their axes; and while so held acting successively on the rim of each can with crimping rollers having different crimping surfaces to effect gas tight closures, substantially as described.

3. In an automatic can closing machine, 110 the combination of a can support; a can holding chuck provided with a yielding friction generating material; means adapted to cause said can to be gripped and held against rotation between said surface and 115 said support and the said material deformed during the crimping operations; a plurality of crimping rollers adapted to successively act on the rim of said can; and means to revolve said rollers around and in contact 120 with said rim to effect an air tight closure, substantially as described.

4. In an automatic can closing machine the combination of a can support; a can holding chuck provided with a yielding friction generating surface of an annular form; means adapted to cause said can to be gripped and held against rotation during 125 the crimping operations between said surface and said support; a plurality of crimp- 130

ing rollers having crimping surfaces of different forms adapted to successively act on the rim of said can; and means to revolve said rollers around and in contact with said rim to effect an air tight closure, substantially as described.

5. In an automatic can closing machine the combination of a can support; a can holding chuck adapted to enter a depression 10 in the top of the can and provided with a yielding friction generating material normally extending below the face of said chuck, adapted to contact with the bottom of said depression and to hold said can 15 against rotation on its axis during the crimping operations; lifting means adapted to cause said material to be deformed and said can to be gripped and held against rotation between said surface and said support; a 20 plurality of crimping rollers adapted to successively act on the rim of said can; and means to revolve said rollers around, and

in contact with, said rim to effect an air tight closure, substantially as described.

6. A chuck for holding cans during the process of automatically closing the same, which comprises a rim adapted to enter the cavity in the can top and whose lower face is provided with a deformable compressible friction generating material adapted to prevent the rotation of the cans during the crimping operations, substantially as described.

7. A chuck for holding cans during the process of automatically closing the same, 35 which consists of a member adapted to overlie the top of the can provided with a recess having a cut away edge and a resilient, compressible deformable friction generating material located in said recess, and adapted 40 to expand into the space formed by said cutaway edge, substantially as described.

In testimony whereof I affix my signature.
EARL D. SMITH.
